UNITED STATES PATENT OFFICE.

HERMAN H. WOLTER, OF MERIDEN, CONNECTICUT, ASSIGNOR TO EDWARD MILLER & CO., OF MERIDEN, CONNECTICUT, A CORPORATION OF CONNECTICUT.

DESIGN FOR A LAMP.

55,923.

Specification for Design. Patented July 20, 1920.

Application filed April 9, 1920. Serial No. 372,668. Term of patent 3½ years.

To all whom it may concern:

Be it known that I, HERMAN H. WOLTER, a citizen of the United States, residing at Meriden, county of New Haven, and State of Connecticut, have invented a new, original, and ornamental Design for a Lamp, of which the following is a specification, reference being had to the accompanying drawing, forming a part thereof.

In said drawing:

The figure is a perspective view of an ornamental lamp embodying the design of my invention.

I claim—

The ornamental design for a lamp substantially as shown.

HERMAN H. WOLTER.
